UNITED STATES PATENT OFFICE.

EDWIN M. WHEELOCK, OF MINNEAPOLIS, EMERY F. WHEELOCK, OF NORTHFIELD, AND
DICKINSON O. WHEELOCK, OF MINNEAPOLIS, MINNESOTA.

GUIDE-WHEEL FOR PLOW-MOTORS.

1,052,870.

Specification of Letters Patent. Patented Feb. 11, 1912.

Application filed March 22, 1909, Serial No. 485,105. Renewed June 10, 1912. Serial No. 702,929.

To all whom it may concern:

Be it known that we, EDWIN M. WHEELOCK, residing at Minneapolis, in the county of Hennepin and State of Minnesota, 5 EMERY F. WHEELOCK, residing at Northfield, in the county of Rice and State of Minnesota, and DICKINSON O. WHEELOCK, residing at Minneapolis, in the county of Hennepin and State of Minnesota, citizens 10 of the United States, have jointly invented certain new and useful Improvements in Guide-Wheels for Plow-Motors, of which the following is a specification.

Our invention relates to traction engines 15 or motors used in plowing; and its object is to provide means for guiding the motor to cause it to travel along the side of a previously formed furrow. This object we accomplish by providing one of the steering- 20 wheels of the motor with a flange, adapted to contact with the unplowed side of the furrow.

Our improvements are illustrated in the 25 accompanying drawings, in which— Figure 1 is a plan view and Fig. 2 a side elevation of an engine or motor embodying our improvements; Figs. 3 and 4 are detail views of portions of the steering devices connected to the front axle; Fig. 5 is a sectional 30 detail of a portion of a steering wheel and its guide-flange.

We have selected for the purpose of illustration, and have shown in the drawings in somewhat diagrammatic form, an explosive- 35 engine motor, which is the type of motor we prefer to use for plowing, but our improvements are adapted to be used in connection with motors of other types.

In the drawings 1 designates the main 40 frame of the motor, 2 the platform for the operator, 3 the explosive engine, 4 the driving-gear, 5 the rear wheels, 6 the front wheels, 7 the divided front axle, 8 the arms pivoted thereon, and 9 the equalizer for the 45 pivoted members of the front axle, all of which parts may be of any usual or suitable construction.

The axle 7 is preferably suspended from the frame 1 by hangers 10, which are stayed 50 by braces 11. The bar 9 is arranged to be reciprocated transversely to the frame 1, and it is provided with cogs 12, constituting a

rack, which is engaged by a pinion 13 that is operated by a steering-rod 14 that extends rearward and is provided with a hand-wheel 55 15 in position to be turned by an operator on the platform 2. The axis of the pinion is journaled in a box 16 supported from the frame by a hanger 17; and a roller-bearing 18 for the bar 9 is supported by the hanger 60 17 below the pinion 13. The rod 14 is connected to the pinion axis by a universal joint 19. It will be apparent that by means of the devices described an operator can reciprocate the bar 9 by turning the rod 14 65 so as to adjust the inclination of the front wheels and thus steer the machine.

A gang of plows (not shown) may be connected to the motor frame in the customary way by chains 20, or rods, or other suitable 70 means, to enable the motor to draw the gang for plowing.

To relieve the operator of the strain and labor of giving constant attention to the steering devices while plowing to cause the 75 motor and plows to move in proper direction with relation to the previously plowed ground, we provide one of the front wheels with a flange 21 on the outer edge of its tread 22. The inner side of the flange is prefer- 80 ably beveled, as shown at 23, and adapted to bear against the land-side of the furrow to prevent the wheel from cutting into the land-side, and also to prevent the motor from moving away from the furrow; and 85 the operator can, by setting the steering-gear in position to give the motor a slight tendency to move in that direction, obviate any tendency of the motor to move in the opposite direction, or toward the plowed ground. 90 Such wheel flange is not only an aid to the operator in steering the machine, but in effect is made to serve as a positive and practically automatic guide for the machine while plowing along the side of a previously 95 formed furrow.

The flange may be formed integrally with or permanently attached to the wheel, but it is preferable to have it detachable. As illustrated, it is detachably secured by means 100 of eye-bolts 24, provided in the beveled ring or flange 21 and bolts 25 provided in the wheel-tread 22 and passed through the eyes of the bolts 24.

Having described our invention, what we claim and desire to secure by Letters Patent is—

The combination with a steering wheel of 5 a plow motor adapted to run on the surface of the ground at the land side of a furrow, of a flange attached to the outer edge of the wheel rim and arranged to enter the furrow and having its inner side beveled for fri-

tional engagement with the land side of the 10 furrow, substantially as set forth.

EDWIN M. WHEELOCK.
